J. B. HALE

BRAIDING MACHINE BODY STRUCTURE

Filed Nov. 2, 1921

Fig. 2.

Inventor:
Joshua B. Hale,
by Emery Bond, James and Harry Allrys

UNITED STATES PATENT OFFICE.

JOSHUA B. HALE, OF PROVIDENCE, RHODE ISLAND, ASSIGNOR TO TEXTILE ENGINEERING COMPANY, OF PROVIDENCE, RHODE ISLAND, A CORPORATION OF RHODE ISLAND.

BRAIDING-MACHINE BODY STRUCTURE.

Application filed November 2, 1921. Serial No. 512,317.

To all whom it may concern:

Be it known that I, JOSHUA B. HALE, a citizen of the United States, and a resident of Providence, in the county of Providence and State of Rhode Island, have invented an Improvement in Braiding-Machine Body Structures, of which the following description, in connection with the accompanying drawings, is a specification, like characters 10 on the drawings representing like parts.

This invention relates to improvements in braiding machine body structures.

In order that the principle of the invention may be readily understood, I have dis- 15 closed a single embodiment thereof in the accompanying drawing, wherein—

Fig. 1 is a plan view of the body structure; and

Fig. 2 is a vertical section on the line 2—2 20 of Fig. 1, cooperating parts being indicated in dotted lines.

Heretofore, so far as I am aware, braiding machines of the general type herein disclosed have been provided with a bottom 25 plate and spaced upstanding supports structurally distinct therefrom as by a nut and thread construction or in some similar manner, the said supports having secured to their upper ends the outer top plate and the 30 inner top plate between which and the quoits the raceways are provided.

Such a construction is open to numerous objections which it is the purpose of my invention to overcome. Owing to the high 35 speed at which braiding machines must be operated under present day conditions, the parts are liable to become loosened and in that event the walls of the raceways for the travelling carriers become so distorted or 40 out of alignment as to interfere with the smooth and proper travel of the carriers.

Other advantages incident to my invention will be referred to hereinafter.

Referring more particularly to the drawing, I have therein indicated at 1 a unitary structure which is preferably formed of cast metal as a single piece and of such shape as to provide rigid supports for all the operating parts.

As clearly shown in the drawing, the body structure 1 is of a general disk form having an upper surface 1' and a lower surface 2.

The upper surface 1' provides at the center thereof what may be termed the inner top portion 3 and provides an outer surrounding portion 4. Between said two integrally united portions are a series of depressions, wells or recesses 5 of substantial depth and diameter, eight such depressions being herein indicated and which are in communication 60 as shown and are without top plate or covering. Such number may obviously be varied within the scope and purpose of my invention.

The bottom of each depression, well or recess 5 is a portion of the lower surface 2 as will be clearly evident from Fig. 2 and is herein shown as provided with a central opening 6 and a surrounding desirably thickened web or wall 7, the latter constituting 70 a seat for the gear stud (not shown) which extends upwardly through the opening 6. The gear stud itself is indicated in dotted lines at 8 at the right hand side of Fig. 2. It will be observed that the inner top portion 3 is composed at its perimeter of a series of curved or concave faces 9 meeting at points 10. Constituting a union between the upper surface 1 and the lower surface 2 is the upright wall composed of said faces 9, 75 the outer surface of which is of the same contour as the perimeter of the top plate member 3. In other words, in the construction herein shown, the web or wall 9 has eight 80 curved faces respectively meeting at points, said faces lying in upright planes.

Each of the depressions, wells or recesses 5 is in and of itself of circular form, the outer wall of each of said depressions or recesses being indicated at 9'. Said wall 9' 90 constitutes another uniting member between the upper surface 1 and the lower surface 2. Desirably outside of the wall 9' at the upper edge thereof is a flange 9'' constituting the outer edge of the upper surface 1.

It will thus be seen that the inner top portion 3 is supported with the utmost rigidity from the lower surface 2, there being no possibility of impairment of the raceways which in practice are between the 100 outer edge of the inner top portion 3 and the inner edge of the outer surrounding portion 4, between which vertical surface are the rotating quoits, one of which is indi-

cated in dotted lines at 10' in Fig. 2 as formed integrally with the gear 8. Thus the raceways for the travelling carriers, one of which is indicated in part at 11, exist between the upright wall or web 9 and that portion of each quoit lying nearest the center of the body structure, on the one hand, and between the outer surrounding portion 4 and that part of each quoit which at any given time lies at a point furthest removed from the center of the body structure. Thus the said upright walls act as guides and supports for the carriers.

This structure gives a rigid construction as well as an elongated support for the carriers.

Desirably and as indicated at 12 in Fig. 2, I provide a number of openings for the escape of lint, dirt, etc., and I also provide an opening 13 for the reception of a driving gear 14.

Viewing Fig. 1, it will be noted that the body structure is provided at opposite points 15, 16 with lateral projections having holes 17, 18 for the reception of posts for the overhead works.

The previous constructions with which I am familiar present a number of difficulties in the assembling of its parts and great difficulty in maintaining the proper alignment or relation of the parts during the life of the machine. In my construction, on the other hand, there is no possibility of parts getting out of alignment and all the rotating parts are firmly supported.

The form of the body structure which desirably is a single integral piece and desirably is a casting, facilitates the machining of the recesses 5 in which the quoits 10' rotate in that the walls of said recesses can be made concentric with the holes 6 for the studs by using said holes as guides to a "pilot" on a boring tool, or similarly employing the stud, over which the boring tool bushing can be placed.

The body structure herein disclosed is of such form that it can be economically molded in a foundry, no cores being used with the pattern.

As already pointed out, the form and rigidity of the one piece of unitary structure present numerous advantages in supporting the driving mechanism as well as the overhead works, viz., the take-up and the wind-up devices.

It will be observed that the construction of the operating parts of the machine and their relation to the body of the machine render necessary the rigid structure herein disclosed.

Desirably I provide a carrier having a broad face, and I have found that the same requires a rigid structure in which to operate, and which is herein disclosed.

In my Patent No. 1,434,205, dated Octo-

ber 31, 1922, I have disclosed a braiding machine which among its elements has a body structure which I herein claim as an article of manufacture. While I have pointed out herein numerous advantages incident to the unitary structure herein disclosed, reference to said companion application will make clear the peculiar cooperation between such unitary structure of the form herein disclosed and the cooperating parts including the travelling carriers and the rotating quoits.

Having thus described one embodiment of my invention, I desire it to be understood that although specific terms are employed, they are used in a generic or descriptive sense and not as terms of limitation, the scope of the invention being set forth in the following claims:

1. A braiding machine body structure wherein the braiding carriers are received, having an inner upright wall and an outer upright wall, spaced apart to form a communicating series of open-top depressions, wells or recesses for the reception of the quoits and wherethrough said carriers may circulate under guidance of said walls and quoits.

2. A unitary or one-piece braiding machine body structure wherein the braiding carriers are received, said unitary or one-piece structure having an inner upright wall and an outer upright wall, spaced apart to form a laterally communicating series of open-top depressions, wells or recesses for the reception of the quoits, and wherethrough said carriers are adapted to circulate under guidance of said walls and quoits.

3. A braiding machine body structure wherein the braiding carriers are received, having an inner upright wall and an outer upright wall spaced apart to form a series of open-top depressions, wells or recesses which are laterally communicating in a ring like formation and which are adapted for the reception of the quoits and wherethrough said carriers are circulated under guidance of said walls and quoits.

4. A braiding machine body structure composed of an integral casting wherein the braiding carriers are received, said integral casting having an inner upright wall and an outer upright wall spaced apart to form a communicating series of open-top depressions, wells or recesses for the reception of the quoits.

5. In a unitary braiding machine body structure wherein the braiding carriers are received, having upright inner and outer walls spaced apart and respectively provided with portions protruding toward each other at intervals to provide a laterally communicating series of open-top depressions, wells or recesses for the reception of the quoits.

quoits and wherethrough said carriers may circulate under guidance of said walls and quoits.

6. A braiding machine body structure wherein the braiding carriers are received, having an inner top portion 3, upright inner and outer walls 9, 9' spaced apart to provide depressions, wells or recesses 5 for the

reception of the quoits, said body structure having the outer surrounding portion 4 and 10 a lower surface 2 constituting the bottoms of said depressions, walls or recesses.

In testimony whereof, I have signed my name to this specification.

JOSHUA B. HALE.
